[57] CLAIM

The ornamental design for a removable cargo shelf for use in a sports utility vehicle, as shown and described.

DESCRIPTION

FIG. 1 is a top, front and end perspective view of the removable cargo shelf for use in a sports utility vehicle showing my new design;

FIG. 2 is a front elevational view thereof;

FIG. 3 is a rear elevational view thereof;

FIG. 4 is an end elevational view thereof, the end opposite being a mirror image of the end shown in FIG. 4;

FIG. 5 is a top plan view thereof; and,

FIG. 6 is a bottom plan view thereof.

FIG. 1.

FIG. 5.

FIG. 2.

FIG. 6.

FIG. 3.

FIG. 4.
